UNITED STATES PATENT OFFICE.

WILLIAM SELLERS, OF PHILADELPHIA, PENNSYLVANIA.

STEAM-HAMMER.

SPECIFICATION forming part of Letters Patent No. 240,555, dated April 26, 1881.

Application filed February 18, 1881. (No model.)

To all whom it may concern:

Be it known that I, WILLIAM SELLERS, of the city and county of Philadelphia, and State of Pennsylvania, have invented certain new 5 and useful Improvements in Steam-Hammers, of which the following is a specification.

My present invention relates to that class of steam-hammers in which the steam-cylinder is secured between two uprights, and in which 10 the hammer-bar is guided by bearings at the top and bottom of the cylinder, and is available with the arrangement of cylinder and hammer-bar described in United States Patent No. 132,373, granted to me October 22, 1872.

15 In double upright hammers of this type, as heretofore constructed, the cylinder has been secured to the uprights by bolts passing through flanges on each side of the cylinder, the bolts being placed closer together at the 20 lower end of the cylinder, where the greatest strain occurs; but with this arrangement these flanges must necessarily sustain all the strains in the plane of the uprights to which the steam-hammer is subjected, and these are so severe 25 that the flanges and uprights are liable to break at this point.

It is one object of my present invention to strengthen the uprights and to relieve the flanges upon the cylinder from strains in the 30 plane of the uprights, while the cylinder remains a guide and key between the uprights to retain them in proper position.

A further object of my invention is to clamp the cylinder between the uprights in such manner that the cylinder shall be more firmly held when the hammer is in service than when at 35 rest; and to these ends my invention consists in providing a cylinder closed at its lower end to the size of the hammer-bar, and combining 40 with this through-bolts extending from upright to upright through the closed end of the cylinder, by which the cylinder is clamped between the two uprights; and it further consists in providing air-passages around these 45 bolts, whereby their temperature is maintained below that of the cylinder during service, so that the bolts will be subjected to a higher strain and the uprights will be more firmly clamped upon the cylinder when the hammer 50 is in operation than when it is at rest.

In the accompanying drawings, which form

part of this specification, Figure 1, Sheet 1, represents an elevation of a steam-hammer embodying my present improvements. Fig. 2, Sheet 2, is a section through Fig. 1 on the line 55 X X. Fig. 3 is a section through Fig. 2 on the line Y Y. Fig. 4 is a section through Fig. 1 on the line W W.

In all the figures similar letters refer to similar parts. 60

A represents the hammer-bar, with detachable and adjustable head D, as described in the hereinbefore-mentioned former patent.

B is the steam-cylinder.

C E are two uprights, the flanges upon which 65 are extended and provided with projecting ribs on each side, so as to embrace the flanges on the cylinder. They are further secured to the cylinder by bolts F, as shown, accurately fitted in both flanges, so as to take all vertical strains. 70

G G are two through-bolts, which pass through the lower and partially-closed end of the cylinder just outside of the stuffing-box for lower end of hammer-bar. They fit as to their ends in the uprights at H H, and are reduced in the middle, as shown, to a diameter about equal to the root of the thread on their outer ends, for the purpose of securing the greatest amount of elasticity without reducing their ultimate strength. The holes through 80 which they pass in both cylinder and uprights are enlarged, as shown at J, thus leaving considerable space for the circulation of air around the bolts. The air enters at K in the lower end of the cylinder, and as it becomes heated 85 passes out at L L in the uprights. The object of thus surrounding the bolts with a free circulation of air is to keep them relatively cooler than the cylinder, so that the expansion of the latter by the heat of the steam during use will cause the bolts to clamp the cylinder still more tightly between the uprights, and thus virtually bind the three castings—that is, cylinder and two uprights—together as one solid piece. 90

The uprights are strongly re-enforced where 95 the bolts G are attached by the rib M, and the strains and vibrations communicated to the uprights are thus distributed over the whole frame of the hammer, instead of being localized at or near the point of attachment of the cylinder to the uprights, as has formerly been the case. It is important that these bolts G 100

G should pass through the cylinder as closely as possible to the outside of the hammer-bar below the piston, as the side strains which occur in forging are transmitted to the framing through the bar, and hence the bolts, to be most effective, should be as nearly as possible in line with the strains, and to attain this end in the best manner it is necessary that the hammer-head should be detachable and the lower cylinder-head cast solid with the cylinder, as described in the hereinbefore-mentioned former patent.

Having now described my invention, what I claim as new, and desire to secure by Letters Patent, is—

1. In a steam-hammer, a steam-cylinder partially closed at its lower end and between two uprights, in combination with bolts which pass through the partially-closed end of the steam-cylinder and the flanges of the uprights, substantially as and for the purposes set forth. 20

2. In a double upright hammer, substantially as described, the bolts G G, in combination with the air-passages K L, all arranged as and for the purposes set forth.

WM. SELLERS.
